RADIO DIRECTION FINDER

Robert H. Worrall, Honolulu, Territory of Hawaii

Application December 8, 1938, Serial No. 244,710
13 Claims. (Cl. 250—11)(Granted under the act of March 3, 1883, as
amended April 30, 1928; 370 O. G. 757)

1

My invention relates broadly to direction finding means, and more particularly to an improved type of radio direction finder.

An object of this invention is to provide an improved type of radio direction finder which can quickly and easily be disassembled for transportation, and readily reassembled, both mechanically and electrically.

Another object of this invention is to provide an improved type of radio direction finder especially suitable for use at high frequencies and useful over a wide frequency range.

Another object of this invention is to provide an improved type of radio direction finder constructed and shielded so as to obtain complete electrical balance between any two corresponding parts and ground.

Another object of this invention is to provide an improved type of radio direction finder which minimizes polarization errors.

A further object of this invention is to provide an improved radio direction finder which is a separate yet complete unit in itself, and which may be used with any well shielded radio receiver.

It is well known to the art that the Adcock radio direction finder is less affected by polarization errors, i. e., so-called "night effect" and refraction, than other types of radio direction finders. The system of Adcock direction finding herein employed is known as a differential system of doublets. In such a system, good results depend upon electrical and mechanical symmetry in construction and upon proper shielding. How this and the above and other objects are accomplished is shown in the description below.

Referring to the drawings,

Fig. 1 is a view, partly in section, of the complete direction finder, except that the right half of the dipole collector assembly and supporting shielding tube, which is exactly like the left half illustrated, is omitted.

Fig. 2 is an end view, partly in section, of the dipole assembly showing the method of supporting and bracing the dipole rods.

Fig. 3 is a sectional view through the longitudinal center of the horizontal shielding tube at 3—3, Fig. 1.

Fig. 4 is an electrical schematic diagram of the entire radio direction finder.

Fig. 5 is a cutaway view looking down on the top of the horizontal shielding tube at 3, Fig. 1, showing schematically how the conducting wires in the horizontal shielding tube have been rotated until they are in a horizontal plane.

2

This radio direction finder comprises the following major parts: the dipole collector assembly, the horizontal shielding tube 19, the vertical shielding tube 20, the tuning and balancing assembly and shield, the coupling system and shield, the bearing assembly, and the interior connectors.

Horizontal shielding tube 19 supports the dipole collector assembly arranged as a pair of 10 horizontally spaced vertical doublets, one doublet at each end. A saddle 23 is permanently secured to the horizontal shielding tube 19 and its lower portion is a smooth, sliding fit around the upper end of the vertical shielding tube 20. There is 15 a locating slot in saddle 23 which engages with pin 22, screwed into tube 20. Set screw 21 locks saddle 23 to tube 20. Shielding enclosure 28, which contains the tuning, balancing and series condensers and the short-circuiting switches for the latter, is secured around tube 20. The lower end of tube 20 is supported in a ball bearing, the lower half 6 of which is secured to the top of 20 shielding housing 13. At its lower end the exterior diameter of shaft 20 is reduced, forming a shoulder 51, which rests upon the upper half 9 of the ball bearing. Set screws 26 secure vertical tube 20 to the upper half 9 of the ball bearing. The ball bearing is separable, the upper half 9 resting on balls 7 which, in turn, are supported 30 by the lower half 6. The tube 20 and the upper half 9 of the bearing rotate about a vertical axis while the lower half 6 of the bearing and the shielding housing 13 remain fixed. The dipoles or collectors 16, 17, horizontal tube 19 and the shielding enclosure 28 all rotate with tube 20. An azimuth scale 8 is secured to the upper half 9 of the bearing. An access door 14, hinged at 27, and locked closed by thumb latch 15, provides access for changing the plug-in coupling coils 61 and 40 62. The supported end of each of the four dipole collector tubes 16 is fitted with a threaded insert 58 which screws on to terminal studs 18. These studs 18 are supported by and secured to insulating strips 50, which are attached by angle fittings 45 to tube 19. An extension rod 17 screws into the unsupported end of each dipole collector tube 16. Insulating strips 47 and 52 form, with metal corner braces 48 (Fig. 2), a bracing frame for dipole collector tubes 16, and are held in position 50 away from tube 19 by insulating pillars 49. The ends of the tube 19 are covered by tightly fitting metal covers 46. Conductor wires 24 are attached to studs 18 and connect the two sets of dipole collectors 16, 17 together in such a manner that the 55 upper dipole collector 16, 17 of each doublet con-

ncts with the lower dipole collector 16, 17 of the doublet at the opposite end of the tube 19. Each wire 24 rotates through 180 degrees in traveling from one pair of dipole collectors 16, 17 to the other. These wires 24 are supported and guided by a number of insulating spacers 42 which fit tightly inside tube 19. There is machined into the rim of each spacer 42 a spline slot into which longitudinal spline 43 engages when the spacers 42 are inserted inside the tube 19. Spline 43 is attached inside and at the top of tube 19 by screws 44. Each pair of spacers 42 is identical except that the slot is shifted along the circumference a definite number of degrees from the vertical varying from 0 degrees to 90 degrees, depending on the position of the spacer or guide 42 along the tube 19. The angular displacement of the slot on the spacers 42 nearest the longitudinal center of tube 19 is 0 degrees from the vertical, and this angle is increased gradually on each spacer 42 along the tube 19 until on the spacer 42 nearest each end of the tube 19, the angle is 90 degrees. Thus, by means of these spacers 42 the common plane of conductor wires 24 is uniformly rotated from the vertical at the ends of tube 19 to the horizontal half way between the ends. At the longitudinal midpoint of tube 19 a spring clip 25 engages the exact electrical center of each of the conductor wires 24. These clips are mounted on terminals 41, which are supported by insulating disc 56. This disc 56 is a close fit inside the upper end of tube 20 and rests upon a shoulder 53. A terminal stud 45 screws into the bottom of each of the two terminals 41 and to these studs the upper ends of down lead wires 31 are connected. The tautness of wires 31 inside vertical shielding tube 20 can be adjusted by screwing terminal studs 45 in or out of terminals 41. The electrical circuit of down lead wires 31 is interrupted by the insertion in each wire of a strain insulator 32. Wires 31 connect to terminal studs 54 which screw into each end of insulators 32. Each insulator 32 is fitted with connectors 33 by means of which the upper and lower portions of wires 31 are connected to the tuning and balancing assembly. The lowermost end of each wire 31 connects to a special terminal 10 which is drilled to receive plug-in coils 61 of standard manufacture. Terminals 10 are supported by insulating disc 51 which fits tightly inside the lower end of tube 20 and rests against shoulder 59. Each of the two series tuning condensers 34 is connected to a pair of terminals 33. A cam operated short-circuiting switch 39 is mounted on the frame of each condenser 34 and one terminal of each switch is connected to a separate group of stator plates of balancing condenser 35. The rotor plates of balancing condenser 35 are grounded to the shield. Knob 37 is mounted on the rotor shaft of balancing condenser 35. Tuning condenser 36 is connected across down lead wires 31. A small variable condenser 38, shown only in Fig. 4, is connected between condenser 36 and the shield. An electrostatic shield 12 is mounted inside coil shield box 13 between coils 61 and coil 11. Coil 11, also of standard manufacture, plugs into jacks mounted on insulating support 30, which is secured to brackets 29 extending from shielding housing 13.

This radio direction finder is made readily transportable by its lightness and ease of assembly and disassembly. To disassemble, dipole collectors 16 with their inserted extensions 17 are unscrewed from terminal studs 18. Horizontal

shield tube 19, with saddle 23 secured thereto, lifts free from vertical tube 20 after set screw 21 is loosened, the locating pin 22 and shoulder 53 insuring that horizontal tube 19 will always assume the same position on tube 20. Lifting tube 19 straight up also frees wires 24 from spring clips 25. The vertical shielding tube 20, with shielding enclosure 28 and top half 9 of the ball bearing secured thereto, can then be lifted clear of the lower half 6 of the ball bearing. Assembly in the reverse order is also quickly and readily accomplished. For lightness, tubes 19 and 20 can be made of Duralumin.

The operation of this radio direction finder is as follows: (refer to Fig. 4) Radio waves striking the collector induce currents in the dipole collectors 16, 17, in the shielding members 19 and 20, and also in the room screen 60 (Fig. 4), if used. The currents induced in the dipole collectors 16, 17 are, of course, the desired currents. The currents induced in the shielding tubes 19 and 20 in turn induce currents into wires 24 and 31, the coils and the other components within the shields 19, 20 and 13. These latter currents set up what is commonly called "antenna effect." The effect of such currents is to induce a signal into the receiver at all times regardless of the position to which the collector is rotated. The "antenna effect" is eliminated in this radio direction finder by so designing and constructing the collector that, without any balancing condenser 35 in the circuit, there is complete electrical balance between any two corresponding parts of the circuit and ground. After this is achieved, the balancing condenser is inserted in the circuit to balance out the small currents which inevitably appear in actual operation. The design and construction of this radio direction finder has approached perfect electrical balance so closely in actual operation that the maximum capacity of the balancing condenser 35 used in this system is only 4.4 micromicrofarads on each side, while the average maximum balancing capacity necessary to use is less than plus or minus 0.2 micromicrofarad over the entire frequency range. The undesirable antenna effect thus eliminated, there remains the desired current induced in the four dipole collectors 16, 17. The desired current travels along wires 24 and 31 to the tuning and balancing system and to coil 61, inducing in coil 11 a similar current which flows to the receiver input through suitable shielded leads. The system is tuned to the desired frequency by condenser 36 and is balanced by condenser 35 for the sharpest bearings. On one frequency band, because of the electrical constants of the system, it is necessary to insert series condensers 34 in the circuit. These condensers are short-circuited when not required by low capacitance, low-loss switches 39, both switches cam operated simultaneously by a single knob. Condenser 38 is adjusted until the capacity of the stator plates of tuning condenser 36 to ground is equal to the capacity of its rotor plates and shield to ground. While the output of the radio direction finder illustrated is magnetically coupled to the receiver input, other types of coupling may be successfully employed. This radio direction finder is useful over a frequency range from 3,000 to 30,000 kcs. and its range may be extended in either direction. This frequency coverage is made possible by the use of plug-in coils.

The sequence of operation for taking bearings with this radio direction finder is as follows, assuming the approximate frequency is known,

the proper plug-in coils inserted and the equipment calibrated. First, set balancing condenser 35 at maximum position on either side. This introduces sufficient unbalance to make the collector function as a good antenna. Second, set tuning condenser 36 for the approximate frequency. Third, tune the receiver around the approximate frequency until a signal is heard. Fourth, tune condenser 36 for maximum signal. Fifth, adjust condenser 35 for minimum signal while rotating the loop. Sixth, make final adjustments of the receiver, condensers 35 and 36. Seventh, rotate loop to position of minimum signal.

It will be understood that the above description and accompanying drawings comprehend only the general and preferred embodiment of my invention and that various changes in construction, proportion and arrangement of the parts may be made within the scope of the appended claims without sacrificing any of the advantages of my invention.

The invention described herein may be manufactured and/or used by or for the Government of the United States of America for governmental purposes without the payment of any royalties thereon or therefor.

What I claim and desire to secure by Letters Patent, is as follows:

1. Direction finding means, comprising a shielding housing, a detachable vertical shielding tube rotatably mounted thereon, a horizontal shielding tube detachably mounted at its longitudinal center on said vertical tube, an upper and a lower vertical detachable collector secured at each end on said horizontal shielding tube and insulated therefrom and from each other, a conductor inside said horizontal shielding tube connecting each said upper collector to said lower collector at the opposite end of said horizontal shielding tube, insulating guide means to rotate the common plane of said conductors from the vertical at each end of said horizontal shielding tube to the horizontal at its center, two down leads extending through said vertical shielding tube, fixed clip means connected to said down leads so located as to engage said conductors in said horizontal shielding tube at the exact center of each, a series condenser connected in each said down lead, a low capacity switch to short circuit each said series condenser, a variable balancing condenser having a separate stator connected to each said down lead and a rotor connected to said vertical shielding tube, a variable tuning condenser connected across said down leads, a variable condenser connected between said tuning condenser and said vertical shielding tube to make the capacity of the stator of said tuning condenser to ground equal the capacity of its rotor and shield to ground, a shielding enclosure for said condensers and switches, a rotatable coil disposed in said shielding housing connected to said down leads and rotating with said vertical shielding tube, a fixed coil mounted in said shielding housing below said rotatable coil and magnetically coupled thereto, an electrostatic shield disposed between said coils, and an azimuth scale attached to said vertical shielding tube.

2. Direction finding means, comprising a shielding housing, a detachable vertical shielding tube rotatably mounted thereon, a horizontal shielding tube detachably mounted at its longitudinal center on said vertical tube, an upper and a lower vertical detachable collector secured at

each end on said horizontal shielding tube and insulated therefrom and from each other, a conductor inside said horizontal shielding tube connecting each said upper collector to said lower collector at the opposite end of said horizontal shielding tube, insulating guide means to rotate the common plane of said conductors from the vertical at each end of said horizontal shielding tube to the horizontal at its center, two down leads extending through said vertical shielding tube, fixed clip means connected to said down leads so located as to engage said conductors in said horizontal shielding tube at the exact center of each, a series condenser connected in each said down lead, a low capacity switch to short circuit each said series condenser, a variable balancing condenser having a separate stator connected to each said down lead and a rotor connected to said vertical shielding tube, a variable tuning condenser connected across said down leads, a variable condenser connected between said tuning condenser and said vertical shielding tube to make the capacity of the stator of said tuning condenser to ground equal the capacity of its rotor and shield to ground, a shielding enclosure for said condensers and switches, a rotatable plug-in coil disposed in said shielding housing connected to said down leads and rotating with said vertical shielding tube, a fixed plug-in coil mounted in said shielding housing below said rotatable plug-in coil and magnetically coupled thereto, an electrostatic shield disposed between said plug-in coils, an access opening in said shielding housing with a closure therefor, and an azimuth scale attached to said vertical shielding tube.

3. Direction finding means, comprising a shielding housing, a detachable vertical shielding tube rotatably mounted thereon, a horizontal shielding tube detachably mounted at its longitudinal center on said vertical tube, an upper and a lower vertical detachable collector secured at each end on said horizontal shielding tube and insulated therefrom and from each other, a conductor inside said horizontal shielding tube connecting each said upper collector to said lower collector at the opposite end of said horizontal shielding tube, insulating guide means to rotate the common plane of said conductors from the vertical at each end of said horizontal shielding tube to the horizontal at its center, two down leads extending through said vertical shielding tube, fixed clip means connected to said down leads so located as to engage said conductors in said horizontal shielding tube at the exact center of each, a series condenser connected in each said down lead, a low capacity switch to short circuit each said series condenser, a variable balancing condenser having a separate stator connected to each said down lead and a rotor connected to said vertical shielding tube, a variable tuning condenser connected across said down leads, a variable condenser connected between said tuning condenser and said vertical shielding tube to make the capacity of the stator of said tuning condenser to ground equal the capacity of its rotor and shield to ground, a shielding enclosure for said condensers and switches, and an azimuth scale fixed on said vertical shielding tube.

4. Direction finding means, comprising a shielding housing, an access opening therein and closure therefor, a vertical shielding tube rotatably mounted on said housing in a separable bearing, the lower half of said bearing secured to said housing, the upper half secured to said

vertical tube, said vertical tube and upper half of said bearing detachable by lifting, a saddle means slidably fitted on the upper end of said vertical tube and detachably secured thereto, a horizontal shielding tube fixedly secured at its longitudinal center to said saddle means and supported thereby, an upper and a lower vertical detachable collector supported at each end of said horizontal shielding tube and insulated therefrom and from each other, a conductor inside said horizontal shielding tube connecting each said upper collector to said lower collector at the opposite end of said horizontal shielding tube, insulating guide means to rotate the common plane of said conductors from the vertical at each end of said horizontal shielding tube to the horizontal at its center, two down leads extending through said vertical shielding tube, fixed clip means connected to said down leads so located as to engage said conductors in said horizontal shielding tube at the exact electrical center of each, a series condenser connected in each said down lead, a low capacity switch to short circuit each said series condenser, a variable balancing condenser having a separate stator connected to each said down lead and a rotor connected to said vertical shielding tube, a variable tuning condenser connected across said down leads, a variable condenser connected between said tuning condenser and said vertical shielding tube to make the capacity of the stator of said tuning condenser to ground equal the capacity of its rotor and shield to ground, a shielding enclosure for said condensers and switches, a rotatable insulated coil mounting fixed in the lower end of said vertical shielding tube and connected to said down leads, a rotatable coil disposed in said shielding housing and plugging in to said rotatable coil mounting, a fixed coil mounting and plug-in coil secured in said shielding housing below said rotatable coil, said fixed and said rotatable coils coupled magnetically, an electrostatic shield disposed between said coils, and an azimuth scale attached to said vertical shielding tube.

5. Direction finding means, comprising a shielding housing, a vertical shielding tube rotatably mounted on said housing in a separable bearing, the lower half of said bearing secured to said housing, the upper half secured to said vertical tube, said vertical tube and upper half of said bearing detachable by lifting, a saddle means slidably fitted on the upper end of said vertical tube and detachably secured thereto, a horizontal shielding tube fixedly secured at its longitudinal center to said saddle means and supported thereby, an upper and a lower vertical detachable collector supported at each end of said horizontal shielding tube and insulated therefrom and from each other, a conductor inside said horizontal shielding tube connecting each said upper collector to said lower collector at the opposite end of said horizontal shielding tube, insulating guide means to rotate the common plane of said conductors from the vertical at each end of said horizontal shielding tube to the horizontal at its center, two down leads extending through said vertical shielding tube, fixed clip means connected to said down leads so located as to engage said conductors in said horizontal shielding tube at the exact electrical center of each, a series condenser connected in each said down lead, a low capacity switch to short circuit each said series condenser, a variable balancing condenser having a separate stator connected to each said down lead and a rotor connected to said vertical shield-

ing tube, a variable tuning condenser connected across said down leads, a variable condenser connected between said tuning condenser and said vertical shielding tube to make the capacity of the stator of said tuning condenser to ground equal the capacity of its rotor and shield to ground, a shielding enclosure for said condensers and switches, and an azimuth scale attached to said vertical shielding tube.

6. Direction finding means, comprising a collector system of dipoles arranged as two horizontally spaced vertical doublets, a rotatable T-shaped support formed by a horizontal and a vertical tubular shielding member, a balanced horizontal transmission line connecting the upper dipole collector of each doublet with the lower dipole collector of the other, a balanced vertical transmission line detachably connected by clip means to the exact electrical center of said horizontal transmission line, said transmission lines contained inside said shielding tubular members, tuning and balancing means connected to said vertical transmission line with a shielding enclosure therefor, a shielding housing, coupling means for said vertical transmission line disposed within said shielding housing, said dipole collectors, tubular shielding members, shielding enclosure and shielding housing symmetrically disposed about a vertical plane through said dipole collectors, said dipole collectors, tubular shielding members and shielding housing symmetrically disposed about a vertical plane through the axis of said vertical tubular shielding member perpendicular to the axis of said horizontal shielding tubular member, said dipole collectors and horizontal shielding tubular member symmetrically disposed about a horizontal plane through the axis of said horizontal shielding tubular member, said dipole collectors, tubular shielding members and shielding housing being detachable.

7. Direction finding means, comprising a collector system of dipoles arranged as two horizontally spaced vertical doublets, a rotatable T-shaped support formed by a horizontal and a vertical tubular shielding member, a balanced horizontal transmission line connecting the upper dipole collector of each doublet with the lower dipole collector of the other, a balanced vertical transmission line detachably connected by clip means to the exact electrical center of said horizontal transmission line, said transmission lines contained inside said shielding tubular members, tuning and balancing means connected to said vertical transmission line with a shielding enclosure therefor, a shielding housing, coupling means for said vertical transmission line disposed within said shielding housing, said dipole collectors, tubular shielding members and shielding housing being detachable.

8. Direction finding means, comprising a collector system of dipoles arranged as two horizontally spaced vertical doublets, a rotatable T-shaped support formed by a horizontal and a vertical tubular shielding member, a balanced horizontal transmission line connecting the upper dipole collector of each doublet with the lower dipole collector of the other, a balanced vertical transmission line detachably connected by clip means to the exact electrical center of said horizontal transmission line, said transmission lines contained inside said shielding tubular members, tuning and balancing means connected to said vertical transmission line with a shielding enclosure therefor, a shielding housing, coupling means for said vertical transmission line dis-

posed within said shielding housing, and an azimuth scale attached to said vertical shielding tubular member, said dipole collectors, tubular shielding members and shielding housing being detachable.

9. Direction finding means, comprising a shielding housing, a detachable vertical shielding tube rotatably mounted thereon, a horizontal shielding tube detachably mounted at its longitudinal center on said vertical tube, an upper and a lower vertical detachable collector secured at each end on said horizontal shielding tube and insulated therefrom and from each other, a conductor inside said horizontal shielding tube connecting each said upper collector to said lower collector at the opposite end of said horizontal shielding tube, insulating guide means to rotate the common plane of said conductors from the vertical at each end of said horizontal shielding tube to the horizontal at its center, two down leads extending through said vertical shielding tube, fixed clip means connected to said down leads so located as to engage said conductors in said horizontal shielding tube at the exact center of each, a series condenser connected in each said down lead, a low capacity switch to short circuit each said series condenser, a variable balancing condenser having a separate stator connected to each said down lead and a rotor connected to said vertical shielding tube, a variable tuning condenser connected across said down leads, a variable condenser connected between said tuning condenser and said vertical shielding tube to make the capacity of the stator of said tuning condenser to ground equal the capacity of its rotor and shield to ground, a shielding enclosure for said condensers and switches, a rotatable coil disposed in said shielding housing connected to said down leads and rotating with said vertical shielding tube, a fixed coil mounted in said shielding housing below said rotatable coil and magnetically coupled thereto, an electrostatic shield disposed between said coils, and an azimuth scale attached to said vertical shielding tube, said collectors, shielding tubes, shielding enclosure and shielding housing symmetrically disposed about a vertical plane through said collectors, said collectors, shielding tubes and shielding housing symmetrically disposed about a vertical plane through the axis of said vertical shielding tube perpendicular to the axis of said horizontal shielding tube, said collectors and horizontal shielding tube symmetrically disposed about a horizontal plane through the axis of said horizontal shielding tube.

10. Direction finding means, comprising a shielding housing, a detachable vertical shielding tube rotatably mounted thereon, a horizontal shielding tube detachably mounted at its longitudinal center on said vertical tube, an upper and a lower vertical detachable collector secured at each end on said horizontal shielding tube and insulated therefrom and from each other, a conductor inside said horizontal shielding tube connecting each said upper collector to said lower collector at the opposite end of said horizontal shielding tube, insulating guide means to rotate the common plane of said conductors from the vertical at each end of said horizontal shielding tube to the horizontal at its center, two down leads extending through said vertical shielding tube, fixed clip means connected to said down leads so located as to engage said conductors in said horizontal shielding tube at the exact center of each, a series condenser connected in each

said down lead, a low capacity switch to short circuit each said series condenser, a variable balancing condenser having a separate stator connected to each said down lead and a rotor connected to said vertical shielding tube, a variable tuning condenser connected across said down leads, a variable condenser connected between said tuning condenser and said vertical shielding tube to make the capacity of the stator of said tuning condenser to ground equal the capacity of its rotor and shield to ground, a shielding enclosure for said condensers and switches, a rotatable plug-in coil disposed in said shielding housing connected to said down leads and rotating with said vertical shielding tube, a fixed plug-in coil mounted in said shielding housing below said rotatable plug-in coil and magnetically coupled thereto an electrostatic shield disposed between said plug-in coils, an access opening in said shielding housing with a closure therefor, and an azimuth scale attached to said vertical shielding tube, said collectors, shielding tubes, shielding enclosure and shielding housing symmetrically disposed about a vertical plane through said collectors, said collectors, shielding tubes and shielding housing symmetrically disposed about a vertical plane through the axis of said vertical shielding tube perpendicular to the axis of said horizontal shielding tube, said collectors and horizontal shielding tube symmetrically disposed about a horizontal plane through the axis of said horizontal shielding tube.

11. Direction finding means, comprising a shielding housing, a detachable vertical shielding tube rotatably mounted thereon, a horizontal shielding tube detachably mounted at its longitudinal center on said vertical tube, an upper and a lower vertical detachable collector secured at each end on said horizontal shielding tube and insulated therefrom and from each other, a conductor inside said horizontal shielding tube connecting each said upper collector to said lower collector at the opposite end of said horizontal shielding tube, insulating guide means to rotate the common plane of said conductors from the vertical at each end of said horizontal shielding tube to the horizontal at its center, two down leads extending through said vertical shielding tube, fixed clip means connected to said down leads so located as to engage said conductors in said horizontal shielding tube at the exact center of each, a series condenser connected in each said down lead, a low capacity switch to short circuit each said series condenser, a variable balancing condenser having a separate stator connected to each said down lead and a rotor connected to said vertical shielding tube, a variable tuning condenser connected across said down leads, a variable condenser connected between said tuning condenser and said vertical shielding tube to make the capacity of stator of said tuning condenser to ground equal the capacity of its rotor and shield to ground, a shielding enclosure for said condensers and switches, and an azimuth scale fixed on said vertical shielding tube, said collectors, shielding tubes, shielding enclosure and shielding housing symmetrically disposed about a vertical plane through said collectors, said collectors, shielding tubes and shielding housing symmetrically disposed about a vertical plane through the axis of said vertical shielding tube perpendicular to the axis of said horizontal shielding tube, said collectors and horizontal shielding tube symmetrically disposed about a horizontal plane through the axis of said horizontal shielding tube.

a horizontal plane through the axis of said horizontal shielding tube.

12. Direction finding means, comprising a shielding housing, an access opening therein and closure therefor, a vertical shielding tube rotatably mounted on said housing in a separable bearing, the lower half of said bearing secured to said housing, the upper half secured to said vertical tube, said vertical tube and upper half of said bearing detachable by lifting, a saddle means slidably fitted on the upper end of said vertical tube and detachably secured thereto, a horizontal shielding tube fixedly secured at its longitudinal center to said saddle means and supported thereby, an upper and a lower vertical detachable collector supported at each end of said horizontal shielding tube and insulated therefrom and from each other, a conductor inside said horizontal shielding tube connecting each said upper collector to said lower collector at the opposite end of said horizontal shielding tube, insulating guide means to rotate the common plane of said conductors from the vertical at each end of said horizontal shielding tube to the horizontal at its center, two down leads extending through said vertical shielding tube, fixed clip means connected to said down leads so located as to engage said conductors in said horizontal shielding tube at the exact electrical center of each, a series condenser connected in each said down lead, a low capacity switch to short circuit each said series condenser, a variable balancing condenser having a separate stator connected to each said down lead and a rotor connected to said vertical shielding tube, a variable tuning condenser connected across said down leads, a variable condenser connected between said tuning condenser and said vertical shielding tube to make the capacity of the stator of said tuning condenser to ground equal the capacity of its rotor and shield to ground, a shielding enclosure for said condensers and switches, a rotatable insulated coil mounting fixed in the lower end of said vertical shielding tube and connected to said down leads, a rotatable coil disposed in said shielding housing and plugging in to said rotatable coil mounting, a fixed coil mounting and plug-in coil secured in said shielding housing below said rotatable coil, said fixed and said rotatable coil coupled magnetically, an electrostatic shield disposed between said coils, and an azimuth scale attached to said vertical shielding tube, said collectors, shielding tubes, shielding enclosure and shielding housing symmetrically disposed about a vertical plane through said collectors, said collectors, shielding tubes and shielding housing symmetrically disposed about a vertical plane through the axis of

said vertical shielding tube perpendicular to the axis of said horizontal shielding tube, said collectors and horizontal shielding tube symmetrically disposed about a horizontal plane through the axis of said horizontal shielding tube.

13. Direction finding means, comprising a shielding housing, a vertical shielding tube rotatably mounted on said housing in a separable bearing, the lower half of said bearing secured to said housing, the upper half secured to said vertical tube, said vertical tube and upper half of said bearing detachable by lifting, a saddle means slidably fitted on the upper end of said vertical tube and detachably secured thereto, a horizontal shielding tube fixedly secured at its longitudinal center to said saddle means and supported thereby, an upper and a lower vertical detachable collector supported at each end of said horizontal shielding tube and insulated therefrom and from each other, a conductor inside said horizontal shielding tube connecting each said upper collector to said lower collector at the opposite end of said horizontal shielding tube, insulating guide means to rotate the common plane of said conductors from the vertical at each end of said horizontal shielding tube to the horizontal at its center, two down leads extending through said vertical shielding tube, fixed clip means connected to said down leads so located as to engage said conductors in said horizontal shielding tube at the exact electrical center of each, a series condenser connected in each said down lead, a low capacity switch to short circuit each said series condenser, a variable balancing condenser having a separate stator connected to each said down lead and a rotor connected to said vertical shielding tube, a variable tuning condenser connected across said down leads, a variable condenser connected between said tuning condenser and said vertical shielding tube to make the capacity of the stator of said tuning condenser to ground equal the capacity of its rotor and shield to ground, a shielding enclosure for said condensers and switches, and an azimuth scale attached to said vertical shielding tube, said collectors, shielding tubes, shielding enclosure and shielding housing symmetrically disposed about a vertical plane through said collectors, said collectors, shielding tubes and shielding housing symmetrically disposed about a vertical plane through the axis of said vertical shielding tube perpendicular to the axis of said horizontal shielding tube, said collectors and horizontal shielding tube symmetrically disposed about a horizontal plane through the axis of said horizontal shielding tube.

ROBERT H. WORRALL.
